UNITED STATES PATENT OFFICE.

LOUIS I. BECKWITH, OF BOSTON, MASSACHUSETTS.

LUGGAGE CARRIER.

Application filed January 30, 1922. Serial No. 532,805.

To all whom it may concern:

Be it known that I, LOUIS I. BECKWITH, a citizen of the United States of America, and resident of Boston (Dorchester), in the county of Suffolk and State of Massachusetts, have invented new and useful Improvements in Luggage Carriers, of which the following is a specification.

This invention relates to luggage carriers

for automobiles and particularly to that type of device adapted to be detachably secured to the running board of the automobile and so constructed as to permit of its being folded into compact form for storage.

Such carriers commonly comprise spaced supporting posts, having means for detachably securing them to the running board of the automobile, and an elongated fence like device extending between and supported by the posts, said device constituting a retainer for baggage resting upon the running board and being frequently formed as an extensible lattice of lazy-tongs type. The end posts usually are provided with members which extend inwardly and transversely across the running board whereby to provide end closures for the luggage receiving space. These end closure members are preferably fixed to the posts and this necessitates the pro-

vision of connections between the posts and the extensible retainer device such as to permit the posts with their end members to be turned relatively to the retainer for folding such end members into parallelism with the retainer device for storage. If the retainer device consists of a lattice or lazy-tongs, special connections between the latter and the posts are usually necessary in order to permit of the collapse of such lazy-tongs

in folding the device. The connections heretofore devised for the above purposes have not proven as satisfactory in practical use as is desirable and the principal object of the present invention is to provide a sup-

porting post having a strong and rigid end closure member secured thereto, together with improved means whereby a front wall or luggage retainer of lazy-tongs construction may be connected to such post in a

manner permitting of the ready unfolding or collapse of the device without possibility of binding or cramping of the parts. As usually devised, luggage carriers have no provision for preventing contact of the

luggage with the running board or with the body of the vehicle and under ordinary road

conditions the vibration of the luggage frequently causes injury to the running board or vehicle body to an extent such that many persons hesitate to employ luggage carriers 60 of this type. The present invention has for a further object the provision of means whereby the protection of the running board and body from such injuries may be facilitated.

In carrying the above objects into effect the supporting post having the end closure member rigidly secured thereto, is provided with elements to which the opposite ends of a hinge bar are pivotally secured. These elements may take the form of outstanding brackets provided with pins upon which angularly disposed end portions of the hinge bar are journaled or if such end post be of circular cross section, 70 the post itself may constitute the pintle of the hinge, passing through journal openings in the angularly bent end portions of the hinge bar. In whatever manner the post and bar be connected, the latter is provided with 75 means for supporting the end portion of the lazy-tongs device. For this purpose the hinge bar is provided with an elongated slot at one or both of its ends for the reception and guidance of pins projecting from the end 80 members of the lazy-tongs device. The collapse and extension of the latter is thus provided for while the interposition of the hinge bar between the lazy-tongs and post serves not only to permit the folding of the 85 structure but also acts to prevent cramping of the parts such as frequently occurs when the lazy-tongs device is connected directly to the post. Preferably the end closure member may comprise a bracket formed as a 90 casting and having a socket for the lower end of a post of circular cross section, together with suitable brace members secured to such bracket and to the post. The bracket is preferably provided with openings for the 100 reception of straps for securing the luggage firmly in position, the openings being so disposed that the straps will extend between the luggage and the vehicle body and running board whereby to serve as buffer means to 105 prevent injury to the latter. In some cases to give additional strength as well as to enhance the appearance of the device, the lazy-tongs may be of duplex construction providing a much closer and more rigid lattice 110 than is usually employed.

While certain specific modes of connecting

the post and bar herein disclosed, as well as desirable connections between the lazy-tongs and bar, it is evident that the attainment of the objects of the invention is not dependent upon the employment of such specific arrangements but may be secured by the use of other and equivalent means.

In the accompanying drawings there is illustrated by way of example a preferred arrangement of parts whereby the above objects may be attained and in such drawings,

Fig. 1 is a front elevation of a complete luggage carrier device of preferred form shown as applied to the running board of an automobile and in partially extended condition;

Fig. 2 is an end elevation of the device of Fig. 1;

Fig. 3 is a fragmentary front elevation of a modified form of the device;

Fig. 4 is a plan, partly in section, of the end post of the device of Fig. 3, showing details of construction; and

Fig. 5 is an end elevation of the device shown in Fig. 3.

Referring to Figs. 1 and 2 the running board of an automobile is indicated at 1. Resting upon the upper surface of such running board is the long arm 2 of a bracket having an integral depending portion 3 arranged to engage the outer edge of the running board, and a second and shorter arm 4 substantially parallel to the first named arm 2. The arm 4 extends beneath the running board and is provided with a threaded opening for the reception of a clamping screw 5, such screw being provided with a clamping pad 6 if desired. The bracket is preferably formed as a casting and is provided with a socket opening 7 adjacent that end thereof at which the clamping screw is located and in such socket is fixedly secured the lower end of a post 8. The upper end of this post, may if desired be provided with an extension of reduced diameter as indicated at 9, which extension passes through an opening in the upper end 10 of a connecting member 11. The member 11 may be of strap iron if desired, although the exact form of this part is immaterial. Part 11 extends in a downwardly inclined direction to the point 12, from whence it extends directly down toward the inner end of the bracket arm 2 to which it is secured at the point 13 by means of the rivet 14 or other suitable means. The extension 9 of the post 8 may be headed over as shown at 15 to retain the part 11 in proper position. Instead of providing the post with a reduced upper portion, such post may have an axial opening in its end in which is engaged a bolt or pin performing the same function as the member 9 above described. If desired a brace member 16 may

extend from the member 11 to the outer end

of the bracket arm 2, being connected to such members respectively at the points 17 and 18. The bracket arm 2 together with the members 11 and 16 forms an end closure member for the luggage carrying space, and while as herein disclosed this end member comprises the parts enumerated, it is evident that changes and modifications in the arrangement of such parts may well be made without changing the function thereof.

The bracket arm 2 is provided with one or more openings such as 19, 20 through which may be passed straps 19, 20, or other buffer means serving to prevent contact of the luggage with the upper surface of the running board or with body of the vehicle. Such straps may be of any desired material, such for example as canvas impregnated with rubber, and may be so designed as also to serve as means for retaining the luggage within the luggage carrier. Extending substantially parallel to the post 8 is a hinge bar 21, such bar having its opposite end portions 22, 23 bent to form ears or lugs lying substantially at right angles to the length of such bar, such ears being provided with aligned openings through which passes the post 8. This post, as illustrated in Figs. 1 and 2, is of a circular cross section and thus may form a pintle pin about which the bar 21 may be swung as an axis. The bar 21 is provided with one or more elongated openings or slits such as 22^a, 23^a arranged intermediate the end portions 22 and 23. Slidably engaging the respective slits are pins 24, 25 projecting laterally from the end slats 26, 27 respectively of a lazy-tongs structure 28 forming a front wall for retaining the luggage upon the running board. The opposite end of the lazy-tongs structure is similarly secured to a bar 29 carried by a post 30 having clamping means 31 at its lower end, such parts being in all respects similar to the corresponding parts hereinbefore described.

If desired, an intermediate post or posts such as 32 may be provided for supporting the lattice structure intermediate the end posts. Such intermediate post 32 is furnished with elongated slots 33, 34 for the reception of guiding pins 35 projecting from the lazy-tongs device at suitable points therein, and such post may be provided with clamping means indicated at 36 whereby it may be secured to the running board.

As herein shown in Figs. 1 and 2 the lazy-tongs device is of duplex construction, that is to say, it comprises four series of intersecting slats instead of the two series commonly employed in such structures. As illustrated at the left-hand side of Fig. 1, the intersecting slats 26, 27 are pivotally secured together at their point of intersection 26^a. A second pair of intersecting slats 36, 37 is also shown, the respective slats be-

ing pivotally connected at points 38, 39 respectively, with the slats 26 and 27, and at points in the latter intermediate their point of connection with each other and the guide pins 24, 25. The slats 36 and 37 are pivotally connected at the point 40, such point lying substantially in the line of connection of the pins 24 and 25. The arrangement of slats just described is continued from one end to the other of the structure, thereby providing a close lattice of durable construction and of more pleasing appearance than that ordinarily employed.

Referring now to Figs. 3, 4 and 5 a modified arrangement of parts is illustrated wherein the supporting post 41 is shown as formed of strap iron provided with a plurality of bracket members 42 secured thereto. These bracket members are preferably furnished with integral projections 44 which extend through openings in the post 41 and headed over as shown at 45. The hinge bar 46 is constructed similarly to the bar 21 previously referred to, having angularly arranged ears 47 provided with openings for the reception of pins 48 whereby such ears are pivotally secured to the respective brackets 42, 43. The hinge bar 46 is furnished with an elongated slot such as 49 at one or both ends, such slot herein being illustrated as being at the lower end only of the bar, and through such slot is passed a guide pin 50 projecting laterally from the slat 51 of the lazy-tongs device. The other end of slat 52 of such lazy-tongs device is pivotally connected to the slat 51 at the point 53 and has its free extremity pivotally secured at 54 to the hinge bar 46. If desired, of course, the end of the slat 52 may be slidably connected to the hinge bar 46 in the same manner as is the end of the slat 51. The lower end of the post 41 is fixedly connected to the vertical portion 55 of a bracket having an upper arm 56 and a lower arm 57, such bracket being illustrated as formed from strap iron. The lower extremity of the post 41 may be bent as indicated at 58 to lie in contact with the lower arm 57 of the bracket and the parts 57 and 58 are furnished with aligned threaded openings for the reception of a clamping screw 59. A connecting member 60 is secured at 61 to the post 41, extending in a generally horizontal direction and then downwardly as shown at 62 for connection with the rear end of the bracket arm 56. The vertical brace member 64 may be employed for connecting the members 60 and 56.

In the operation of either of the forms of device above described, the end posts are firmly clamped to the running board with the end closure members carried thereby extending transversely across the width of the running board and defining the length of the space provided for the reception of the

luggage. The lazy-tongs device which constitutes a retainer for preventing the luggage from falling outwardly over the edge of the running board is extended in accordance with the length of the space desired and in all positions of extension of the device forms a secure retainer for the luggage. The employment of intermediate supporting posts provides additional strength and rigidity when the lazy-tongs device is fully extended. When the device is to be removed for storage, it is merely necessary to loosen the clamping screws, whereupon the lazy-tongs may be collapsed and the end members comprising the bracket arms and the posts may be swung to lie in substantial parallelism with the collapsible retainer device. If desirable the parts may be so proportioned that when folded, the bracket arms of the end members lie immediately above the clamping device carried by the central post. Such clamping device may then be brought into clamping engagement with the lower surface of such brackets whereby they are retained in folded position.

I claim:

1. A luggage carrier comprising an end post, a retainer device, a hinge bar arranged substantially parallel to the post, means for pivotally securing said bar to the post, and means for connecting the retainer device to said bar for movement relative to the bar.

2. A luggage carrier including a running board engaging arm having portions for spanning the running board, a clamp carried by one of said portions, the other of said portions being formed with an upwardly projecting rib and integral socket, said rib having strap receiving apertures therein.

3. A luggage carrier comprising an end post, means for securing said post to the running board of an automobile, a hinge bar, means for pivotally connecting said bar and post comprising elements extending substantially at right angles to the length of the bar, said elements having journal openings therein, and a luggage retainer device having one end thereof secured to said bar.

4. A luggage carrier comprising a normally stationary end post, a hinge bar, means for pivotally connecting said post and bar comprising an outstanding ear adjacent to each end of said bar, said ears having journal openings therein, and a retaining device of lazy-tongs construction having one end thereof secured to said bar intermediate said ears.

5. A luggage carrier comprising a normally stationary end post, a hinge bar extending substantially parallel thereto, said bar having outstanding ears journaled to turn about the axis of said post, said bar having a longitudinal slot therein, a lazy-tongs device comprising intersecting and pivotally connected slats, and a pin project-

ing from one of said slats and slidably engaging said slot.

6. A luggage carrier comprising a normally stationary end post of circular cross section, a hinge bar having angularly disposed end portions, said end portions being provided with journal openings through which the post extends, said bar having longitudinal slots therein, and a lazy-tongs device comprising a pair of pivotally connected slats, each of said slats being provided with an outstanding pin which has sliding engagement with one of the respective slots.

7. A luggage carrier for automobiles comprising a bracket having clamping means at one of its ends for securing it to the running board of an automobile, a post having its lower end secured to said bracket at a point adjacent to said clamping means, a member having angularly disposed end portions, one of such end portions being connected to the top of the post and the other to that end of the bracket remote from the clamping means, a bar hingedly secured to the post, and a luggage retainer connected to said bar.

8. A luggage carrier for automobiles comprising a bracket having a clamping device for securing it to the running board of an automobile, said bracket having a socket opening adjacent to one end thereof, a post having its lower end fixedly secured in said socket, a member extending substantially parallel to the post and hingedly connected thereto, and a lazy-tongs device having one of the ends connected to said member.

9. A luggage carrying device comprising a front wall or retainer, end members, means for clamping such device to a running board, and a buffer member secured to and connecting the end pieces whereby said buffer will extend between the car and luggage positioned within such device.

10. A luggage carrier comprising attaching posts and a double lattice lazy-tong connecting the posts, said double lattice lazy-tong having terminal central pivot members secured to the end posts and lateral guide members interlocking with the posts.

11. A luggage carrier having end closures comprising elements normally extending transversely of the running board, and means for securing such luggage carrier to the running board of an automobile, said elements having openings therein, and longitudinally extending buffer devices secured in the openings and connecting the transverse elements.

12. In a running board luggage carrier, the combination with a duplex lazy-tong lattice, comprising slats and pivots connecting the slats of a supporting post therefor having a running board engaging clamp, said post having a central aperture for engagement with a pivot of the lazy-tong and having spaced longitudinally extending slots, the lazy-tong having members slidably mounted in the slots.

Signed by me at Boston, Massachusetts, this 31st day of December, 1921.

LOUIS I. BECKWITH.
